(57) **CLAIM**

The ornamental design for middle sliding rail for drawer, as shown and described.

DESCRIPTION

FIG. 1 is a perspective view of a middle sliding rail for drawer showing my new design;

FIG. 2 is a front view thereof, the opposite side being a mirror image;

FIG. 3 is a top plan view thereof;

FIG. 4 is a bottom plan view thereof; and,

FIG. 5 is a left side view thereof, the opposite side being a mirror image.

Portions of the middle sliding rail for drawer are shown broken away in FIGS. 1, 3, 4, and 5 to indicate indefinite length.
